BINDER ROLLING CONSTRUCTION

Sigurd Clausen, Brooklyn, N. Y., assignor to International Cigar Machinery Company, a corporation of New Jersey

Application May 7, 1938, Serial No. 206,561

5 Claims. (Cl. 131—53)

This invention relates to cigar machines and more particularly to improved rolling mechanism for forming cigar bunches.

The chief object of this invention is to achieve a simplicity in construction which will greatly benefit the operation of a cigar machine by the provision of a simplified rolling pin structure so designed that the number of elements required for each unit has been materially reduced with a concurrent increase in general machine efficiency.

The invention also consists of an improved rolling pin mechanism wherein the rolling pin has been mounted on a movable carriage provided with self-aligning pin supporting bearings which allow changes of rolling pins for various selected cigar shapes to be effected with a minimum of expenditure in time and effort.

It is a further object of the invention to provide improved rolling pin mechanism having means for adjusting the pin at any desired angle with respect to the rolling table and mounts which allow rolling pins to be changed with a minimum of effort whenever a different taper of cigar is to be formed on the machine.

The invention is further characterized in the provision of adjustable rolling pin supporting mechanism so constructed and arranged that the means which control the movement and operation of the rolling pin are mounted below the plane of the rolling table thereby making it possible to eliminate control or operating mechanism such as stationary trailer cam means which have been previously used in some cigar machines of this type.

With these and other objects not specifically mentioned in view, the invention consists in certain combinations and constructions which will be hereinafter fully described, and then specifically set forth in the claims hereunto appended.

In the accompanying drawing which forms a part of this specification, and wherein the several reference characters designate the same or like elements:

Fig. 1 is a partial plan view of binder apron rolling mechanism;

Fig. 2 is a sectional elevation of Fig. 1;

Fig. 3 is an end elevation of Fig. 1; and

Fig. 4 is a sectional diagrammatic view showing the filler charge being rolled into a tapered shape in the rolling apron by the tapered rolling pin.

The construction herewith presented has a flexibility covering the entire range of shapes

of cigars, from cylindrical to any amount of taper of body.

When producing cigars with cylindrical bodies a straight rolling table and a straight rolling apron are used with a cylindrical rolling pin, but when producing cigars with tapered bodies it has been found desirable to use an apron and a rolling table having a curvature corresponding to the taper of the cigar, and operated by a conical rolling pin, the apex of which should be approximately the same as the apex of the conical body of the cigar. The curvature of the rolling table and the apron should also be struck from the apex point above mentioned.

15 The rolling pin housing 11 receives its motion from a cam disk on the drive shaft (not shown) by cam lever 12 through an adjustable connecting rod 13.

The housing 11 has two pairs of rollers, one 20 pair 14 on vertical pins 15 and one pair 16 on horizontal pins 17. These rollers travel in cam tracks 18 and 19, respectively. The curvature of these tracks is struck from the apex point of the conical rolling pin 20.

25 The cam tracks 18 and 19 are preferably formed in an adjustable bracket 140 attached to the rolling table 21 by screws 27. The holes 27a for these screws in the rolling table 21 are elongated in order to provide for shifting the bracket 140, and its cam tracks formed therein, to move the rolling pin 20 to or from the table.

The rolling pin 20 at one end is mounted in self-aligning bearings 22 and 23, one bearing 22 being located in the main part of housing 11 35 and the other bearing 23 being fixed in housing 24 adjustably secured to the main housing 11 by screws 26 passing through slotted openings 36a in order that bearing 23 may be quickly adjusted to any desired position. The rolling pin

30 20 is provided with a shaft portion 20a. A shoulder 20b of rolling pin 20 serves to hold a retaining flange 20c against bearing 22, and a sleeve 20d on shaft 20a is provided to space the bearings 22 and 23, said parts of the bearing unit

45 being secured in position by a retaining washer 20e and by a screw 26f, which threads into the end of shaft 20a. The screw holes 26a in housing 24 are slotted so as to permit the adjustment of housing 24 as above described. The term

50 "self-aligning" is used herein to indicate the fact that when the angle of the axis of pin 20 relatively to the part 21 is changed by shifting the housing 24, the bearing 22 does not require any change to be made manually, inasmuch as the arcuate disposition of its rings permits the balls

to function properly at all angular positions of the pin 20.

When a conical rolling pin is to be used, screws 26 are loosened and housing 24 with its included bearing 23, is shifted a suitable amount until the bottom surface of the conical rolling pin 20 has been brought parallel to the top of the rolling table 21. As the bearing 23 is shifted down in a straight line it causes a slight horizontal displacement of bearing 22 which is automatically accomplished by allowing the outer bearing race to float in housing 11. The other end, or the outboard end of rolling pin 20 is mounted in an adjustable bracket 290 provided with a cam track 29 in which runs a cam follower 30 mounted on the end of a rolling pin. In Fig. 2 is shown a completed adjustment for a conical rolling pin.

While making this adjustment the bracket 290 containing cam track 29 for the outboard follower 30 of the rolling pin 20 is removed; and at the completion of the adjustment it is replaced and secured at a height corresponding with the adjusted position of cam follower 30. Elongated slots 31a for screws 31 are formed in bracket 290 thereby permitting the bracket to be adjustably attached to the machine thus making it possible to regulate the position of cam track 29.

After adjustments have been completed and a filler-charge 32 has been deposited on the apron 33, the rolling pin housing 11 through its connections, as before described, starts a forward motion, the rolling pin 20 picks up the slack of the apron 33 which envelopes the filler charge 32 and rolls it on the rolling table 21. As it advances, the apron is pulled taut by a drum 34 (Fig. 4) thus squeezing the filler charge 32 in the apron 33 between the rolling pin 20 and the table 21.

As the rolling operation proceeds the filler charge 32 rolls over and is enveloped by the binder leaf 35 which has been deposited and held, by succession, in a predetermined position on the apron 33.

As the binder leaf 35 is placed on the apron and before the rolling movement starts, the paste applicer of paster mechanism, not shown, deposits paste on the binder leaf for securing the filler in the binder.

At the end of the rolling operation the bunch is dropped over the edge of the rolling table 21 ready to be transferred by conventional means (not shown) for the wrapping and finishing operations.

The invention above described may be varied in construction within the scope of the claims for the particular device, selected to illustrate the invention, is but one of many possible concrete embodiments of the same. The invention is not, therefore, to be restricted to the precise details of the structure shown and described.

What I claim is:

1. In a cigar machine, the combination with a bunch rolling table and a bunch rolling apron, of a rolling pin coacting with said apron, a carriage supporting one end of said rolling pin, a longitudinally extending set of bearings for said rolling pin comprising longitudinally spaced bearing elements carried by said carriage and positioned at one end of said rolling pin, and means for moving one of said set of bearing elements relative to the other to adjust the position of the rolling pin above said table.

2. In a cigar machine, the combination with a bunch rolling table and a rolling apron, of a rolling pin coacting with said apron to form bunches

therein, an adjustably supported bracket mounted at one side of said table, a plurality of cam tracks formed in said bracket, in planes at an angle to each other, a carriage provided with cam followers mounted for reciprocatory movement in said cam tracks, respectively, and an adjustable set of spaced apart bearings for supporting said pin exclusively at one end, mounted in said carriage, said bearings comprising a bearing element at one end adjustable manually to vary the angle of operation of the rolling pin, and another bearing element constructed and arranged to accommodate its alignment to each of the manually variable adjustable positions of said adjustable bearing element.

3. In a cigar machine, the combination with a bunch rolling table and a rolling apron, of a rolling pin coacting with said apron to form bunches therein, an adjustably supported bracket mounted at one side of said table, cam tracks formed in said bracket, a carriage provided with cam followers mounted for reciprocatory movement in said bracket, said carriage supporting said pin at one end thereof, an adjustable set of bearings mounted in said carriage for supporting said pin exclusively at said end, and means for adjusting one bearing of said set relatively to another bearing of said set whereby the position of said pin with respect to said table may be varied, the other bearing of said set being constructed and arranged to accommodate its alignment to each of the variable adjustable positions of said adjustable bearing element.

4. In a cigar machine, the combination with a bunch rolling table and a rolling apron, of a rolling pin coacting with said apron to form bunches therein, an adjustably supported bracket mounted at one side of said table, cams formed in said bracket, said cams comprising a cam track formed in a horizontal plane and a cam track formed in a vertical plane, said bracket being movable bodily to adjust both of said cam tracks simultaneously, a single carriage provided with cam followers mounted for reciprocatory movement along said tracks in said bracket, said carriage supporting said pin exclusively at one end thereof, an adjustable set of bearings mounted in said carriage for adjustment of the pin exclusively at one end, and acting to support the pin exclusively at one end of the pin, an outboard cam follower mounted at the other end of said rolling pin, and an adjustable cam bracket cooperating with said follower.

5. In a cigar machine, the combination with a bunch rolling table, a rolling apron, and a rolling pin coacting with said apron to form bunches therein, of a rolling pin supporting member, said member supporting said pin at one end only, a set of spaced bearings mounted in said member for supporting said pin, said bearings comprising a bearing element at one end of said member adjustable manually to vary the angle of operation of the rolling pin, and another bearing element constructed and arranged to accommodate its alignment to each of the manually variable adjustable positions of said adjustable bearing element, and means constructed and arranged to move said supporting member to and fro, constituting the exclusive means for actuating said rolling pin throughout the bunch rolling cycle, and said latter means being constructed and arranged to act solely through said supporting member.

SIGURD CLAUSEN.
